UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed May 29, 1923. Serial No. 642,235.

To all whom it may concern:

Be it known that I, EDWIN E. BARNEY, citizen of the United States, and resident of New Rochelle, in the county of Westchester and State of New York, have invented certain new and useful Improvements in Typewriting Machines, of which the following is a specification.

My invention relates to typewriting machines, and more particularly to a small, compact, portable machine intended to be transported or carried in its carrying case, such a machine, for example, as the Remington portable machine.

15 In portable machines it is desirable to confine the length of the platen as much as possible, consistent with the requirements for writing on paper of standard widths, and to accordingly confine the length of the 20 carriage in order not to exceed the necessary widthwise dimensions of the machine. One difficulty, however, that presents itself in thus restricting the machine to taking paper of approximately standard widths, is that 25 work sheets of greater widths, and more particularly standard large sized envelopes cannot be introduced into the machine without folding them, which is undesirable.

One object of my invention is to provide 30 a construction which overcomes this difficulty and enables comparatively wide work sheets, or standard large sized envelopes, to be introduced in unfolded condition into and be properly fed through the machine, 35 and in which it is unnecessary to increase the length of the platen or the carriage, to attain the results.

Another object of my invention is to provide 40 a novel construction and arrangement of parts, including a finger piece for turning the platen which may be moved from an expanded position for use to a compact position where it enables the machine to be enclosed within its carrying case.

45 In the accompanying drawings, wherein like reference characters indicate corresponding parts in the different views,

Figure 1 is a detail fragmentary rear elevation, with parts in section and parts 50 omitted, of a Remington portable machine embodying my invention and conditioned for transportation within its carrying case.

Figure 2 is a detail fragmentary rear view with parts in section, of the platen and the means for supporting it at the right-hand end; the finger wheel being shown in its expanded position for use. 55

Figure 3 is a fragmentary end view, with parts broken away, of the carriage and some of the associated parts as seen from the right. 60

Figure 4 is a detail fragmentary front elevation, with parts in section, of the right-hand end portion of the carriage and some of the associated parts. 65

Figure 5 is an end view of the carriage and associated parts as seen from the left, and with parts in section.

Figure 6 is a detail perspective view of the right-hand combined carriage end plate 70 and off-set bracket arm.

Figure 7 is a detail perspective view of the right-hand platen head, and an extension member forming part thereof.

I have shown my invention in the present 75 instance embodied in a Remington portable machine, but have illustrated only so much of said machine as is necessary to disclose my invention in its inclusion therein. The invention may be readily employed in such 80 a machine without material modification of its existing structural features except by the substitution of parts, as will hereinafter more clearly appear. It should be understood, however, that the invention is 85 not restricted to its employment in such machines.

In the Remington portable machine, as at present marketed, and as disclosed in the application of Joseph B. Holden Serial No. 90 533,945, filed February 3, 1922, a platen 8½ inches long is employed, which enables a full written line to be produced on standard sized sheets, which do not exceed 8½ inches in width. However, such machines 95 do not enable a large sized standard envelope of 9½ inches to be used in the machine without folding such envelope. By my present invention, a work sheet or envelope of 9½ inches in width may be used without folding 100 it, and without increasing the length of the platen or carriage, so that the machine may be received within the same carrying case that is now in use, and without eliminating

any of the advantages which accrue to the said machine as it is now employed.

In the Remington portable machine, a carriage support 8 is mounted at its rear 5 end for fore-and-aft case shifting movement on parallel arms 9. These arms are fixed on a rock shaft 10, pivoted at its reduced ends 11 in the frame 12 of the machine. The upper ends of the arms 9 are 10 pivoted at 13 to lugs 14 on the carriage support. The shiftable support 8 carries a carriage comprising a main carriage bed 15 mounted in the usual manner on bearing rollers (comprising rollers 16) to travel 15 along the support 8. The carriage and associated parts remain substantially as they formerly were except at the right-hand end of the carriage. At this end the usual carriage end plate has substituted therefor a 20 member, preferably formed as a combined end plate and bracket arm, designated as a whole by the reference numeral 17, and shown detached and in detail in Fig. 6. This member is preferably made of sheet 25 metal and comprises a foot piece 18 secured by screws 19 to the carriage bed 15. Projecting upwardly from this foot piece is a carriage end plate 20, preferably formed as shown, with all parts thereof arranged outside 30 of lines coincident with the cylindrical surface of the platen, so as not to extend into the path of a work sheet *a* that may overlap the right-hand end of the platen, as will be understood from a consideration of 35 Figs. 3 and 4. Projecting outwardly and horizontally from the foot piece 18 for a considerable distance beyond the end plate 20, and beyond the right-hand end 21 of the carriage bed, is a bracket arm 22. Projecting upwardly from this arm 22 at the outer end thereof is a support or bracket arm 23, provided with a central opening 24 concentric with the platen 25. This opening in the present instance is 40 of slightly less diameter than the platen, and the walls 26 thereof form a bearing, as will hereinafter appear.

The right-hand platen head 27 is apertured at 28 (Fig. 6) to receive screws 29 that 45 are threaded into the wooden core 30 of the platen, and thus firmly secure the platen head to the platen. Extending outwardly from and preferably integral with the platen head, is a cylindrical extension 31 arranged concentrically with the platen, and 50 preferably having a diameter about equal to that of the platen. This extension is provided with side openings 32 through which the operator's fingers may pass to gain access to the finger piece or wheel 33. The 55 outer edge 34 of the extension constitutes an abutment which bears against the inner face of the bracket arm 23; the latter acting as a thrust bearing to prevent a longitudinal 60 displacement of the platen to the right, 65

or to the left as the parts are viewed in Fig. 2.

The platen head 27, as usual, contains a central bore 35 into which extends a spline projection 36 fixed on the head. A spindle 37 extends through the bore 35 and projects at all times out beyond the right-hand end of the platen. This spindle preferably extends throughout the length of the platen, 70 and is seated at its left-hand end in a bearing carried by the left-hand end plate of the carriage, and forms a support for the platen at such end. The spindle 37 is provided with a spline groove 38 that receives the spline projections 36; causing the spindle and platen to turn together but permitting a limited longitudinal movement of the spindle relatively to the platen. A pin 39 is fastened to the spindle and projects into the spline groove 38 at one end thereof. This pin coacts with the spline projections 36 on the platen head to limit the outward movement of the spindle, as shown in Fig. 2.

Referring more particularly to Figs. 1 and 2, it will be seen that the finger wheel 33 in the present instance is constructed of two rigidly united parts. One part is a hard rubber grip 40, which has a metal bushing 41 fixedly secured thereto; corrugations 42 on the periphery of the bushing aiding in securing the bushing and grip to turn together. One end of the bushing is provided with an integral disk or flange 43 that has a central bore to receive the spindle 37. A spline projection 44 extends from one side of this bore into the spline groove 38, to connect the finger wheel and spindle to turn together but permit the finger wheel to receive a sliding movement on the spindle. A screw 45 is threaded into a 90 tapped opening in the right-hand end of the spindle, so as to act as a stop to limit the outward movement of the finger wheel on the spindle. It will be observed that the diameter of the disk 43 corresponds to the diameter of the grip 40, and that both diameters correspond to the inner diameter of the cylindrical extension 31, and to the bearing opening 24 in the bracket arm 23. It will be seen, moreover, that the finger wheel 33, 95 whether in the contracted position shown in full lines in Fig. 1, or in the expanded position indicated in Fig. 2, receives a support in the bearing in the bracket arm 23, and thus supports the platen at this end thereof. In the expanded position the periphery of the metal disk 43 of the finger wheel is seated in the bearing opening in the bracket arm 23 and provides an effective support 100 and bearing for the platen at this time when the platen and the machine are conditioned for use. I prefer to employ a cap or screw 46 that is received in a tapped opening in the bore of the bushing 41 of the finger wheel, thus closing the outer end of said 105 110 115 120 125 130

bore. The inner end of the screw 46 also constitutes a contact which coacts with the screw 45, to cause the spindle 37 to be moved in after the finger wheel receives a preliminary limited telescoping movement into the extension 31.

The left-hand end of the spindle 37 is received and adapted to move longitudinally and to turn in a bearing member 47 in the left-hand end plate 48 of the carriage in the usual manner. As is usual in the Remington portable machine, and as is disclosed in the application of Joseph B. Holden, Serial No. 547,128, filed March 27, 1922, a member 49 is pivoted at 50 on the left-hand end plate of the carriage. This member 49 is provided with a locking finger 51 that is received in a transverse slot 52 in the bearing member 47, and is adapted to 20 extend across the bearing opening therein, as shown in Fig. 5. The member 49 is also provided with a depending locking member or projection 53, adapted to be received in a recess 54 (see Fig. 1) of a spring locking latch 55, secured at one end to the carriage support 8. In the present instance this locking latch is secured to the carriage support 8 about $\frac{1}{16}$ of an inch further to the left than ordinarily.

30 The member 49 also has an arm 56 which carries a laterally bent finger piece 57, located in the rear of a carriage releasing arm 58 which terminates in a finger piece 59. This arm 58 is connected to a supporting plate 60, mounted on the carriage by pivots 61 and carrying a feed rack 62, which normally engages the lowermost feed dog 63 to restrain the power driven carriage against movement in the direction of its feed.

40 It will be understood that the finger 51 normally extends into the path of the left-hand end of the spindle 37, as shown in Fig. 5, and prevents a longitudinal displacement of the spindle to the left. This prevents the finger wheel from being moved to the limit of its movement within the cylindrical member 31, and prevents it from being moved in far enough to clear one of the side walls 50 64 of the cover of the carrying case for the machine. Therefore, in this condition, the cover is prevented from being closed to enclosed the machine.

55 In order to condition the machine for enclosure within its carrying case, the operator, aside from contacting the type bars in the usual manner, presses forward on the finger piece 57, and then moves the finger wheel 33 to the limit of its movement to the left. The effect of actuating the finger piece 60 57 is to move the locking finger 51 out of the path of the spindle 37, move the locking projection 53 down into effective position and move the carriage releasing arm 58 forward, thereby releasing the feed rack

62 to free the carriage. While the parts are thus maintained by pressure exerted by the operator on the finger piece 57, the finger wheel 33 is moved in to the full line Fig. 1 position, as explained. The first part of 70 the movement of the wheel 33 slides it on the spindle 37 until the cap screw 46 reaches the screw 45. The spindle is then picked up and moved to the left in the platen, projecting the left-hand end of the spindle 75 across the path of the locking finger 51. This prevents a return movement of the member 49 to normal position under the action of its spring 65, and thereby locks the projection 53 in effective position and locks 80 the feed rack free from the normally engaged feed dog. The carriage is then moved from its off-centered position in either direction, to a substantially centered position in its line of travel, and when a substantially 85 centered position is reached, the members 53 and 55 of the center lock automatically coact to lock the carriage against travel in either direction from said centered position. With the machine thus conditioned 90 the cover may be closed and the machine enclosed within its carrying case.

To re-condition the machine for use it is merely necessary after removing the cover to expand the type bars in the usual manner, 95 and then move the finger wheel 33 from the full to the dotted line position in Fig. 1. The finger openings 32 in the cylindrical extension, which surrounds the wheel 33 at this time, gives ready access to the wheel 100 for this purpose. The first part of this outward movement of the finger wheel to the position of use, is effected independently of the spindle 37, and until the bottom wall 66 in the bushing reaches the overlapping 105 head of the screw 45, when the spindle will be picked up and moved to the right with the finger wheel to the Fig. 2 position. The effect of this is to withdraw the left-hand end portion of the spindle out of 110 the path of the finger 51. The spring 65 will then return the member 49 to the normal position shown in Fig. 5, thereby rendering the center lock ineffective, and returning the carriage to the restraint of its escape- 115 ment mechanism by permitting the feed rack to return to normal position under the action of its springs 67.

120 While I prefer to employ the finger wheel 33 in combination with the other features disclosed to control the center lock and carriage release, yet, from certain aspects of my invention, it is immaterial whether the finger wheel be employed in such a combination.

125 It will be understood that in the specific construction as disclosed in the present instance, when a $9\frac{1}{2}$ inch envelope or work sheet *a* is in the machine and overlaps the right-hand end of the platen to the capacity 130

of the machine, as shown in Fig. 4, the finger wheel when in position for use extends outside of the arm 23 and beyond the range of the envelope or work sheet, where the finger wheel may be used effectively without interference from or interference with the envelope or work sheet.

It will be seen, moreover, that the inner face of the bracket arm 23 acts as a side edge gage by which a large envelope or work sheet *a* that overlaps the right-hand end of the platen may be properly introduced, and not be interfered with in its feed movement through the machine between the paper apron 68 and the platen 25.

Various changes may be made in the construction shown and described, and parts thereof may be employed without others without departing from my invention as it is defined in the accompanying claims.

What I claim as new and desire to secure by Letters Patent, is:—

1. In a typewriting machine, the combination of a carriage, a cylindrical platen carried thereby, a finger wheel connected with the platen, and a support on the carriage coacting with the finger wheel to support the platen at one end.

2. In a typewriting machine, the combination of a carriage, a cylindrical platen carried thereby, a finger wheel connected with the platen to turn therewith but to be shifted axially of the platen relatively thereto from an expanded position for use to a compact position, and a support on the carriage on which said finger wheel is supported for turning and shifting movement and by which the platen is supported at one end through said finger wheel.

3. In a typewriting machine, the combination of a carriage, a cylindrical platen carried thereby, a finger wheel connected with the platen, and a support on the carriage having a central bearing opening therethrough in which said finger wheel is seated and through which the finger wheel is adapted to move from the outer side of said support to the inner side thereof.

4. In a typewriting machine, the combination of a carriage, a cylindrical platen carried thereby, a finger piece for turning the platen, said finger piece being movable from an expanded position for use to a compact position, and a bearing on the carriage for said finger to support it for turning and sliding movements and through said finger piece to support the platen at one end.

5. In a typewriting machine, the combination of a carriage, a cylindrical platen carried thereby, a finger piece for turning the platen, said finger piece being movable from an expanded position for use to a compact position, and a bearing on the carriage having a bearing opening to receive and support said finger piece for turning and

sliding movements and through said finger piece to support the platen at one end, the finger piece moving through said bearing opening in the movement of the finger piece from the expanded to compact position.

6. In a typewriting machine, the combination of a carriage, a cylindrical platen carried thereby, an extension projecting outwardly from and axially of the platen at one end thereof, a finger piece for turning the platen, said finger piece being movable from an expanded position for use to a compact position, and a bearing on the carriage for said finger piece to support it for turning and sliding movements and through said finger piece to support the platen at one end, the finger piece in moving to said compact position passing into said extension.

7. The combination of a cylindrical platen, a support therefor at one end having its bearing for the platen arranged at a considerable distance outwardly from and beyond the end of the platen that is supported thereby, and a finger wheel operatively connected with the platen to turn it and movable from an expanded position for use outside of said supporting bearing to a contracted position between the bearing and the end of the platen supported thereby.

8. The combination of a cylindrical platen, a cylindrical extension that projects outwardly from one end of the platen, a bearing that coacts with the outer end of said cylindrical extension for preventing an axial movement of the platen in one direction, and a finger wheel operatively connected with the platen for turning it and movable from an expanded position for use outside of said cylindrical extension to a contracted position within said extension.

9. The combination of a cylindrical platen, an extension fixed to and projecting outwardly from one end of the platen but not beyond an extension of the cylindrical surface thereof, a bearing member, and a finger wheel operatively connected with the platen to turn it and movable from an expanded position for use beyond the said bearing to a contracted position within the extension, the finger wheel being supported in said bearing and thereby supporting the platen at one end.

10. The combination of a cylindrical platen, a platen spindle that has a telescoping movement in the platen from an expanded position to a contracted position, and a finger piece that has a telescoping movement on said spindle from an expanded to a contracted position.

11. The combination of a cylindrical platen, a platen spindle that has a telescoping movement in the platen from an expanded position to a contracted position, a finger piece that has a telescoping movement on said spindle from an expanded to a contracted position.

a contracted position, and a bearing for that end of the platen which carries said finger wheel arranged outside of and at a considerable distance beyond the said end of the 5 platen and between which bearing and the end of the platen the finger wheel is received when moved to contracted position.

12. The combination of a cylindrical platen, a cylindrical extension of substantially the same diameter as the platen projecting outwardly from one end thereof and forming a support for a work sheet that overlaps said end of the platen, a finger piece for turning the platen, and means 10 which enable said finger piece to be shifted from an expanded position outside of said extension to a contracted position within the extension.

13. The combination of a cylindrical platen, a cylindrical extension of substantially the same diameter as the platen projecting outwardly from one end thereof and forming a support for a work sheet that overlaps said end of the platen, a finger 15 piece for turning the platen, means which enable said finger piece to be shifted from an expanded position outside of said extension to a contracted position within the extension, and a support for one end of the 20 platen coacting with said finger piece.

14. The combination of a cylindrical platen, a cylindrical extension of substantially the same diameter as the platen projecting outwardly from one end thereof and 25 forming a support for a work sheet that overlaps said end of the platen, a finger piece for turning the platen, means which enable said finger piece to be shifted from an expanded position outside of said extension to a contracted position within the 30 extension, and a support for one end of the platen coacting with said finger piece.

15. The combination of a cylindrical

platen, a cylindrical extension of substantially the same diameter as the platen projecting outwardly from one end thereof and 35 forming a support for a work sheet that overlaps said end of the platen, a finger piece for turning the platen, and means which enable said finger piece to be shifted from an expanded position outside of said extension to a contracted position within the 40 extension, said extension having one or more finger openings therein to give access to the finger piece and facilitate moving the same to expanded position.

16. The combination of a cylindrical platen, a cylindrical extension of substantially the same diameter as the platen projecting outwardly from one end thereof and forming a support for a work sheet that 45 overlaps said end of the platen, a finger

piece for turning the platen, means which enable said finger piece to be shifted from an expanded position outside of said extension to a contracted position within the extension, and a support for one end of the 70 platen coacting with said finger piece, said support extending beyond the periphery of said extension to form a side edge gage for a work sheet.

17. The combination of a carriage, a cylindrical platen carried thereby and terminating at one end approximately at an end of the body portion of the carriage, a bracket arm that extends outwardly beyond said end of the carriage and is provided with a bearing arranged beyond the end of the body of the carriage and beyond where the platen terminates, a spacing member bridging the space between said bearing and the associated end of the platen, 75 a finger piece for turning the platen, and means for enabling said finger piece to be moved from an expanded position outside said bearing to a contracted position in the space between said bearing and the associated end of the platen. 80

18. The combination of a carriage, a cylindrical platen carried thereby and terminating at one end approximately at an end of the body portion of the carriage, a 95 bracket arm that extends outwardly beyond one end of the carriage and is provided with a bearing arranged beyond the end of the body of the carriage and beyond where the platen terminates, an extension 100 on the platen bridging the space between said bearing and the associated end of the platen, a finger piece for turning the platen, and means for enabling said finger piece to be moved from an expanded position outside said bearing to a contracted position in the space between said bearing and the associated end of the platen, the finger piece in moving to contracted position passing through the bearing in said bracket 105 110 arm.

19. The combination of a carriage, a cylindrical platen carried thereby, a bracket arm carried by the carriage and having a bearing opening therein in alignment with 115 the platen, an extension projecting outwardly from one end of the platen and bearing at its outer end against the bracket arm and leaving an intervening space between said bracket arm and the associated end of the 120 platen to receive a work sheet that overlaps the end of the platen, a finger piece for turning the platen and receiving a bearing in a bearing opening in said bracket arm, and means for enabling said finger piece to be 125 shifted from its expanded position for use outwardly from the bracket arm to a contracted position between said arm and the end of the platen, the finger piece in moving to contracted position passing through 130

said opening in the bracket arm and into said extension.

20. The combination of a carriage, a cylindrical platen carried thereby, an end plate at one end of the carriage that does not pass inwardly beyond the cylindrical surface of the platen or an extension of said surface so as not to interfere with a work sheet that overlaps an end of the platen, an off-set bracket arm situated outwardly beyond said end plate at a considerable distance therefrom, a bearing in said bracket arm, an extension projecting outwardly from an end of the platen and bearing against said bracket arm, a finger piece for turning the platen, and means for enabling said finger piece to be shifted from an expanded position for use outwardly beyond said bracket arm to a contracted position between the bracket arm and an end of the platen.

21. The combination of a carriage, a cylindrical platen carried thereby, an end plate at one end of the carriage that does not pass inwardly beyond the cylindrical surface of the platen or an extension of said surface so as not to interfere with a work sheet that overlaps an end of the platen, an off-set bracket arm situated outwardly beyond said end plate at a considerable distance therefrom, a bearing in said bracket arm, an extension projecting outwardly from an end of the platen and bearing against said bracket arm, a finger piece for turning the platen, and means for enabling said finger piece to be shifted from an expanded position for use outwardly beyond said bracket arm to a contracted position between the bracket arm and an end of the platen, the finger piece receiving a support in a bearing opening in said bracket arm to support the platen at one end and in passing to contracted position moving through said bearing opening.

22. The combination of a carriage, a cylindrical platen carried thereby, an end plate for the carriage at one end thereof located outwardly beyond one end of the platen and outside of or beyond the cylindrical surface of the platen or an extension thereof so as not to interfere with a work sheet that overlaps the end of the platen, an off-set bracket arm situated outwardly beyond said end plate at a considerable distance therefrom and from the end of the platen and having a bearing opening aligned with the platen, a cylindrical extension on the platen of a diameter approximately that of the platen and bearing at its outer end against said bracket arm, a finger wheel for turning the platen, and means which enable said finger wheel to be shifted from its expanded position for use outwardly beyond said bracket arm to a contracted position between said bracket arm and said end of the platen and into said cylindrical extension, the finger

wheel in moving to contracted position passing through said bearing opening in the bracket arm.

23. The combination of a carriage, a cylindrical platen carried thereby, an end plate for the carriage at one end thereof located outwardly beyond one end of the platen and outside of or beyond the cylindrical surface of the platen or an extension thereof so as not to interfere with a work sheet that overlaps the end of the platen, an off-set bracket arm situated outwardly beyond said end plate at a considerable distance therefrom and from the end of the platen and having a bearing opening aligned with the platen, a cylindrical extension on the platen of a diameter approximately that of the platen and bearing at its outer end against said bracket arm, a finger wheel for turning the platen, a spindle telescoping in the platen, and means for enabling the finger wheel to slide on said spindle for a limited distance whereby the finger wheel may be shifted inwardly from its expanded position for use at the outside of said bracket arm through said bearing opening to a contracted position between the bracket arm and the end of the platen and into said extension.

24. The combination of a carriage, a cylindrical platen carried thereby, a bearing on the carriage for supporting one end of the platen, said bearing being at a point which is outside of and at a considerable distance beyond an end of the platen and an end of the carriage, a finger wheel for turning the platen, and means which enable said wheel to be shifted from an expanded position for use outside of said bearing to a contracted position between said bearing and an end of the platen.

25. The combination of a carriage, a cylindrical platen carried thereby, a bearing on the carriage for supporting one end of the platen, said bearing being at a point which is outside of and at a considerable distance beyond an end of the platen and an end of the carriage, a finger wheel for turning the platen, and means which enable said wheel to be shifted from an expanded position for use outside of said bearing to a contracted position where substantially all of the finger wheel will be contained within a space between a vertical plane passing through said bearing and the associated end of the platen.

26. The combination of a carriage, a cylindrical platen carried thereby, a bearing on the carriage for supporting one end of the platen, said bearing being at a point which is outside of and at a considerable distance beyond an end of the platen and the associated end of the carriage, a finger wheel for turning the platen, and means which enable said wheel to be shifted from

- an expanded position for use where the finger wheel in the main is outside of the bearing to a contracted position where said finger wheel in the main is at the inner side 5 of said bearing or between the bearing and the associated end of the platen.
27. The combination of a carriage, a cylindrical platen carried thereby, a bearing on the carriage for supporting one end of the 10 platen, said bearing being at a point which is outside of and at a considerable distance beyond an end of the platen and an end of the carriage, a finger wheel for turning the platen, and means which enable said wheel 15 to receive a telescoping movement on the bearing to a contracted position where the wheel overlaps the bearing and extends between the bearing and the associated end of the platen.
28. The combination of a carriage, and a bracket secured to the carriage and having an off-set platen supporting arm located at a considerable distance outwardly from the 20 associated ends of the platen and carriage so as to enable a work sheet to extend a considerable distance beyond said end of the platen without obstruction from said bracket arm.
29. The combination of a carriage, a bracket secured to the carriage and having an off-set platen supporting arm located at a considerable distance outwardly from the 25 associated ends of the platen and carriage so as to enable a work sheet to extend a considerable distance beyond said end of the platen without obstruction from said bracket arm, and a finger wheel that in the main may be positioned between said bracket arm and the associated end of the platen.
30. The combination of a carriage, a cylindrical platen carried thereby, a bearing on the carriage for supporting one end of the platen, said bearing being at a point which is outside of and at a considerable dis-
- tance beyond an end of the platen and the 45 associated end of the carriage, a finger wheel for turning the platen, means which enable said wheel to be shifted from an expanded position for use outside of said bearing to a contracted position 50 where substantially all of the finger wheel will be contained within a space between a vertical plane passing through said bearing and the associated end of the platen, escapement mechanism for the carriage, and 55 means controlled by said finger wheel when it is shifted to compact position for locking the carriage free from restraint of its escapement mechanism.
31. The combination of a cylindrical 60 platen, a platen spindle that has a telescoping movement in the platen from an expanded position to a contracted position, a finger piece that has a telescoping movement on said spindle from an expanded to a contracted position, a center lock for locking the carriage substantially centered in its 65 line of travel, and means whereby said spindle locks the center lock in ineffective condition.
32. The combination of a cylindrical 70 platen, a platen spindle that has a telescoping movement in the platen from an expanded position to a contracted position, a finger piece that has a telescoping movement on said spindle from an expanded to a contracted position, escapement mechanism for the carriage, and means controlled by said spindle for maintaining the carriage free 75 from restraint of its escapement mechanism.
- Signed at the borough of Manhattan, city of New York, in the county of New York, and State of New York, this 28th day of May A. D. 1923.

EDWIN E. BARNEY.
